UNITED STATES PATENT OFFICE.

JOSEPH MATHE, OF OMAHA, NEBRASKA.

STEAM-VULCANIZER.

1,218,100.

Specification of Letters Patent.

Patented Mar. 6, 1917.

Application filed August 28, 1916. Serial No. 117,125.

To all whom it may concern:

Be it known that I, JOSEPH MATHE, citizen of the United States, residing at Omaha, in the county of Douglas and State of Nebraska, have invented certain new and useful Improvements in Steam-Vulcanizers, of which the following is a specification.

This invention relates to an improvement in steam vulcanizers of the class adapted for use in reforming or repairing outer or inner rubber vehicle tires, and has for its object, broadly, to provide an apparatus for this purpose which will be convenient in use for applying heat, coincidentally, to rubber tires of various diameters, the parts to be few and simple so that manufacture will be economical, and so arranged that the work of vulcanizing may be performed conveniently.

20 The invention includes the combination with a boiler for producing steam, of a vulcanizing receptacle having continuous, outer and inner concavo-convex walls to provide an upright, annular container in which the 25 rubber tires may be deposited for the purpose of being heated, said container being provided adjacent to its outer and inner sides and bottom with a concavo-convex casting to form, in cross-section, an intermediate 30 steam chamber of substantially U-shape, lids or covers of segmental form being provided for the heating chamber and arranged to swing outwardly, and an apertured, horizontal, annular partition being provided for 35 supporting the tires in the chamber and being movable for conveniently removing said tires, when heated, steam being admitted to the upper part at one of the sides of the U-shaped chamber, and a discharge port for 40 condensed steam being provided for said chamber to communicate with the boiler, said discharge port being disposed at the bottom and at substantially 180 degrees from the intake of the chamber tending to cause 45 the uniform circulation of the heat or steam.

The invention consists of the novel construction, combination and arrangement of parts as described herein and claimed, and as illustrated in the accompanying drawing, it being understood that changes in form, size, proportion and minor details may be made in accordance with the appended claims without departing from the spirit of the invention or sacrificing any of its advantages.

In the drawing, Figure 1 is a side view of

the apparatus, the boiler being partly broken away and the vulcanizing receptacle being in vertical section. Fig. 2 is a plan view of the vulcanizing receptacle, the lids being swung to an open position. Figs. 3 and 4 are enlarged detail views to clearly illustrate construction, Fig. 3 being a sectional view showing a fastening means for connecting the segmental lids to the inner wall of the U-shaped chamber, and Fig. 4 being a side view of the same. Fig. 5 is a transverse section through the vulcanizing receptacle and steam chamber on line 5—5 of Fig. 1, the tires and apertured partition being removed. Fig. 6 is a plan view of the apertured, annular partition. Fig. 7 is a sectional view of the partition on line 7—7 of Fig. 6. Fig. 8 illustrates a grip-rod used for removing the annular supporting plate or partition from the heating chamber.

Referring now to the drawing for a more particular description, numeral 8 indicates a continuous wall of U-shape in cross-section to provide an annular container 9 in which the rubber tires 10 may be deposited, a similar wall 11 of greater dimensions being provided and disposed outwardly and adjacent to wall 8 to provide, intermediately, an annular heating chamber 12, a plurality of inwardly projecting spacing-lugs 13 being provided for the wall 11 below its top; and the upper end of said wall 11, at its respective outer and inner sides is provided with inwardly projecting, annular, horizontal flanges 14 and 14'.

As thus described, the walls 8 and 11 may be maintained parallel and in spaced relation, so that the outer and inner parts of chamber 12 may be of substantially uniform width, each of the walls 8 and 11 being transversely curved at their bottoms, as best shown in Fig. 1, and as indicated at a.

Numerals 15 indicate lids arranged to cover the container 9, each lid having a wall b formed with an upward, transverse curvature as well as having a longitudinal curvature. The lids are provided with flanges 16 and 17 on their respective outer and inner edges, their ends also being provided with flanges c, and each lid is hinged, as indicated at 18, upon the outer wall 11, at uniform distances apart, at the junction of said wall 11 and the horizontal flange 14.

As thus described, several tires 10 may be placed in the container 9, the form of the lids, when closed, facilitating in providing

a required space, said container being of such width that several tires of various diameters may be simultaneously heated.

At 19 is indicated a steam boiler, preferably heated by means of a gas burner 20. It is provided with a pipe 21 communicating with the annular chamber 12 near the top of wall 11, and is provided with a return pipe 22 communicating with the bottom of chamber 12. Pipe 22 communicates with a hollow casing 23 used as a mold for repairing tires, and a pipe 24 communicates with the hollow casing 23 and with the boiler, preferably near the bottom of said boiler. Numeral 25 indicates a valve to control a movement of steam from the casing 23 to the boiler through a pipe 26, and numeral 27 indicates a blow off valve for the boiler; and by regulating this valve 27 the certain degree of steam pressure or heat best adapted for vulcanizing may be maintained, this degree of heat being indicated by a thermometer 28.

Numerals 29 indicates an annular supporting-plate or partition having hooks 30 projecting from its upper side and provided with numerous apertures 31. It is adapted to be seated in engagement with wall 8, near the curved part *a* of said wall, in the container 9. In operation, the lids being swung to an open position, and resting upon ledges 32 with which the outer part of the wall 11 is provided, the tires are placed in the container. The lids are then closed and are secured by means of latches 33 which are pivotally mounted in the staples 34 with which the inner part of wall 11 is provided, said latches engaging the catches 35 of the flanges 17 of said lids. Steam under control of valve 36 then passes through pipe 21 to enter the heating chamber, an adequate degree of heat being employed for vulcanizing, and the steam, more or less condensed, will return to the boiler through pipes 22 and 24 and the intermediate casing 23.

It will be understood that the tires, after being heated, will be in a condition more or less plastic, and care should be exercised so that their removal from the container will not be attended with injury. After the lids have been swung outwardly, all of the tires may be elevated and removed without injury, the annular plate or partition 29 being moved upwardly by any suitable means, the means herein shown being gripping-bars 37 having loops 38 which are adapted to engage the hooks 30 of said plate.

By referring to Figs. 1 and 6 it will be seen that the apertures 31 of the plate 29 permit the heat to circulate or move upwardly from the curved bottom of the casing 8 for heating the tires.

Since the lids 15 are arranged to swing

outwardly to an open position, as best shown in Fig. 2, an operator may have convenient access to the chamber 9 for depositing the tires therein or for removing the annular plate 29 together with the tires. Also since the lids are supported by the ledges 32, when swung outwardly, the work will be facilitated in the matter of opening or making a closure of the container 9.

Having fully described the construction what I claim as my invention and desire to secure by Letters Patent is,—

1. In combination with an upright, endless casing of U-shape in cross-section, a second upright, endless casing of U-shape in cross-section provided at its top with opposed, inwardly projecting flanges, said second casing being disposed outwardly of and adjacent to the first named casing, its flanges engaging the sides at the top of said first named casing to provide an annular chamber below the flanges intermediate said casings, means for heating said annular chamber, and a plurality of lids of segmental form each having a hingeable connection with the second casing and adapted to make a closure of a part of the first named casing.

2. In combination with an upright, endless casing of U-shape in cross-section, a second upright, endless casing of U-shape in cross-section provided at its top with opposed, inwardly projecting flanges, said second casing being disposed outwardly of and adjacent to the first named casing, its flanges engaging the sides of said first named casing to provide an annular chamber intermediate said casings and below said flanges, means for heating said annular chamber, a plurality of lids of segmental form each having a wall curved longitudinally and transversely and provided at its sides with flanges, said lids being hingeably connected with the second casing at the junction of one of the inwardly projecting flanges thereof and adapted to have movements for engaging their flanges with the inwardly projecting flanges of said second casing.

3. In combination with an upright, endless casing of U-shape in cross-section, a second upright, endless casing of U-shape in cross-section provided at its top with opposed, inwardly projecting flanges and provided with outwardly projecting brackets, said second casing being disposed outwardly of and adjacent to the first named casing, its flanges engaging the sides of said first named casing to provide an annular chamber below the flanges intermediate said casings, means for heating said annular chamber, a plurality of lids of segmental form hingeably connected with the second casing and adapted to have swinging movements inwardly of the casings for covering the

first named casing and adapted to have outward swinging movements for uncovering said first named casing, each lid during its outward swinging movement being adapted to engage one of said brackets.

4. An apparatus for vulcanizing vehicle tires, comprising an upright endless casing of U-shape in cross-section for containing the tires, a second upright, endless casing of U-shape in cross-section disposed outwardly of and adjacent to the first named casing, one of said casings being provided at its top with transverse flanges and provided intermediate its top and bottom with spacing-lugs, means for heating the space between the second casing and first named casing, a plurality of lids of segmental shape hinge-

ably connected with the outer side of the second casing, said outer casing being provided at its outer side with brackets for supporting the lids when swung in one direction.

5. In combination with an upright, hollow, annular casing of U-shape in cross-section, segmental lids mounted upon and arranged to swing from the top for covering or uncovering the casing, and means for heating the casing.

In testimony whereof, I have affixed my signature in presence of two witnesses.

JOSEPH MATHE.
